UNITED STATES PATENT OFFICE.

WILLIAM H. BRANDT, OF HUBBARD, IOWA.

CLOSURE DEVICE FOR EGG-CRATES AND THE LIKE.

1,401,236.

Specification of Letters Patent. Patented Dec. 27, 1921.

Application filed April 5, 1921. Serial No. 458,818.

To all whom it may concern:

Be it known that I, WILLIAM H. BRANDT, a citizen of the United States, residing at Hubbard, in the county of Hardin and 5 State of Iowa, have invented a certain new and useful Closure Device for Egg-Crates and the like, of which the following is a specification.

The object of my invention is to provide 10 a closure device for egg crates and the like, which is of simple, durable and comparatively inexpensive construction.

More particularly my invention relates to 15 a device for holding the lid of a crate securely to the crate without the use of nails or the like. The parts being so arranged that they may be quickly and readily placed in position for holding the lid in place, or may be readily and easily removed therefrom.

20 Still another object is to provide socket members for engaging the ends of the lid of the crate and a portion of the crate. The socket members being connected together by yielding devices whereby the socket 25 members will be held in position when once in use.

When these and other objects in view invention consists in the construction, arrangement and combination of the various parts 30 of my device, whereby the objects contemplated are attained, as hereinafter more fully set forth, pointed out in my claims, and illustrated in the accompanying drawings, in which:

35 Figure 1 is a perspective view of a crate with my improved closure device shown thereon.

Fig. 2 is a sectional view taken on the line 2—2 of Fig. 1 showing how the socket 40 member receives the crate and the lid.

Fig. 3 is a detail, perspective view of a portion of one of the socket members; and

45 Fig. 4 is a plan view of a portion of the blank from which the socket members are formed.

In the accompanying drawings I have used the reference numeral 10 to indicate an ordinary crate which is provided with end walls 11.

50 The lower edge of the end walls 11 are provided with reinforcing cleats 12 and the upper ends of the end walls 11 are provided with reinforcing cleats 13. The parts just described are of the ordinary crates 55 now used for shipping eggs.

The crate 10 is provided with a lid 14 which is ordinarily a flat thin board. The lid 14 extends over the reinforcing cleats 13 of the crate 10.

Ordinarily the lid 14 is nailed to the 60 cleats 13.

My device is designed to hold the lid in place without the use of nails, and comprises a pair of socket members A which are formed from a single blank of material. 65

The socket members A include a top 15, sides 16, and a bottom 17. The bottom 17 is of less width than the top 15 as shown in the drawings in Fig. 2.

Fig. 4 shows the blank for forming the 70 socket; and the top 15 is provided with a lip 18 having an opening 19 therein.

The sides 16 are provided with a lip 20 having an opening 21 therein. While the bottom 17 is provided with a lip 22 having 75 an opening 23 therein.

The parts are bent upon the dotted lines shown in Fig. 4 to the position shown in Fig. 3 of the drawings. When in this position the openings 19, 21 and 23 register with 80 each other.

A rivet 24 is extended through the openings for securely holding the lips 18, 20 and 22 against any movement, thus securely holding the socket members A in proper 85 position.

Each end of the sockets A are provided with wires 25 which are secured to the rivet 24. The free ends of the wires 25 are connected to a coil spring 26, as shown in 90 Fig. 1 of the drawings.

The side walls 16 of the socket members A are provided with handle portions 27.

In the practical operation of my device the lid 14 is placed upon the crate 10, one of the 95 socket members is placed over the cleat 13 and the end of the lid 14, as shown in Fig. 2.

The other socket member is engaged in the handle 27 and the springs 26 are slightly extended so as to permit the socket member 100 to be swung over the cleat 13 on the opposite side of the crate. As soon as the socket member is released the tension of the springs will draw the socket members toward each other thus causing each of the cleats and the 105 ends of the lid 14 to be received within the socket member A.

When it is desired to remove my closure device one of the socket members A is engaged and by pulling against the action of 110

the springs 26 it may be moved so that the free edge of the bottom 15 will be permitted to pass over the cleat 13.

As soon as one of the socket members is removed from the crate the remaining socket member will slip off of the crate.

It will be seen that by the use of the single rivets 24 in the ends of the socket members A I am able to securely hold the socket members in position and the rivets form a convenient means for securing the wires 25 thereto.

It will be seen that my device can be made very cheap and is very easy to operate and 15 will do away with the use of nails for holding lids to the crates.

It will be understood that in a great many instances when eggs are brought to town in crates of the type now used it is necessary to 20 nail the lid thereon. By the use of nails the lids can only be used a very few times and are then ineffective, due to splitting. My device does away with this serious objection.

25 Some changes may be made in the construction and arrangement of the parts of my machine without departing from the real spirit and purpose of my invention, and it is my intention to cover by my claims, any 30 modified forms of structure or use of mechanical equivalents, which may be reasonably included within their scope.

I claim as my invention:

1. In a device of the class described in 35 combination with a crate and a lid therefor, a pair of socket members, each comprising a top wall, a bottom wall, a side wall and end walls, the end walls of each socket being yieldingly connected together so that the 40 sockets may be placed on a crate and over the ends of the lid for holding the lid in position on the crate.

2. A means for holding a lid to a crate comprising a pair of socket members having

their ends yieldingly secured together and 45 handles formed in said socket members for permitting the grasping of said sockets.

3. In a device of the class described in combination with a crate and a lid therefor, a pair of socket members, each comprising 50 a top wall, a bottom wall, a side wall and end walls, a handle formed in said side wall, the end walls of each socket being yieldingly connected together so that the sockets may be placed on a crate and over the ends of the 55 lid for holding the lid in position on the crate.

4. In a device of the class described in combination with a crate having cleats on its ends and a lid therefor, a pair of channel 60 shaped sockets each comprising an upper and lower wall connected together by a side wall and having its ends inclosed, said upper wall being designed to rest upon one end of the lid of the crate and said lower wall to be 65 received below the cleat of the crate and means for yieldingly connecting the ends of said sockets together, the parts being so arranged that the ends of the lid and the cleats 70 are received in said sockets for preventing undesired movement of the lid relative to the crate.

5. In a device of the class described in combination with a crate having cleats on its ends and a lid therefor, a pair of channel 75 shaped sockets each comprising an upper and lower wall connected together by a side wall, the upper and lower wall being so spaced as to snugly receive the end of the lid and the cleat of the crate, and means for 80 yieldingly connecting said sockets together, the parts being so arranged that the ends of the lid and the cleats are received in said sockets for preventing undesired movement of the lid relative to the crate.

Des Moines, Iowa, March 29th, 1921.

WILLIAM H. BRANDT.
